HARRY FRANK ROSE, OF NEW YORK, N. Y., ASSIGNOR TO THE ADAMS MFG. CO., INC.,
OF NEW YORK, N. Y., A CORPORATION OF NEW YORK

MULLING APPARATUS

Application filed May 5, 1931. Serial No. 535,196.

This invention relates to mulling apparatus, by which is meant, in the art of manufacturing shoes and other footwear, apparatus for softening box-toe stiffeners and the like. In that art, box-toes are produced by means of suitable stiffening material arranged under the leather or other material of which the vamp is made. One widely used stiffening material is composed of two or 10 more layers of cotton fabric, impregnated with a starch composition adapted to give the desired stiffness when dry but capable of being softened by moistening or dampening so that the impregnated fabric (cut to proper 15 form and size) can be molded or shaped over the toe of the last, after which the subsequent drying restores the original stiffness.

This softening may conveniently be accomplished by means of apparatus of the character described in my copending application, Serial No. 461,937, filed June 18, 1930, a desirable form of that apparatus including one or more racks on which the stiffening pieces or "toes" may be mounted, an open water- 25 containing vessel, and a mulling vessel or chamber. The mounting racks may be plates provided with coil springs of the close type fastened thereto in such manner that the adjacent turns of the springs will form spring 30 clips to hold the pieces of impregnated fabric. Both the water vessel and the mulling chamber are provided with means for receiving one or more of these racks, and the method of softening the pieces comprises first dipping 35 the racks in the water vessel for a few moments and then placing them in the mulling chamber for as long as desired, so that the water soaks into the pieces, thoroughly softening them.

While apparatus of this character is both satisfactory and time-saving, it has been found that under certain circumstances of use there is danger that the workmen employing the apparatus may inadvertently leave 45 the stiffening pieces in the water vessel for more than a few moments. Such treatment of the apparatus is likely to occur, for example, in exceptionally busy shops or in small establishments where there are no men especially detailed to carry out the mulling

operation; a busy workman might place one or more racks in the water vessel, and then after being suddenly called to another job or another part of the shop, forget to remove the racks from the water for a considerable 55 time. If the stiffening pieces employed are of the starch-impregnated cotton variety, for instance, such neglect of the apparatus, accidental or otherwise, is damaging and wasteful; the starch composition may be 60 soaked wholly or partly out of the pieces, or the latter may otherwise become too soggy for proper use.

Accordingly, it is a principal object of the present invention to provide satisfactory and 65 efficient apparatus for softening box-toe stiffeners and the like which may be used without danger of over-softening or otherwise damaging the stiffeners.

It is a further object of the invention to 70 provide mulling apparatus of convenient and portable form which will be fool-proof and incapable of negligent misuse in the hands of ordinary workmen, and also to provide such apparatus which will be inexpensive 75 and of such construction as to permit rapid manipulation of operating parts.

Other objects of the invention are to provide apparatus of the class described having a wetting tank for stiffeners with means for 80 positively preventing accidental over-moistening of the latter, and also to provide such apparatus with convenient means for holding the stiffeners in readily accessible position out of the tank; as well as to provide 85 such apparatus in which racks for supporting the stiffening pieces may be readily and repeatedly interchanged. To these and other ends the invention comprises the novel features and combinations hereinafter described. 90

One desirable embodiment of the invention is shown in the accompanying drawings, in which:

Figure 1 is a perspective view of the apparatus with certain portions cut away and 95 the stiffener rack removed;

Fig. 2 is a side elevation of the apparatus partly in section;

Fig. 3 is a perspective view of the support on which the stiffener rack rides; and 100

Fig. 4 is an enlarged vertical section of part of the stiffener rack, showing the coil spring for holding the stiffeners.

A tank 10 which may desirably be shaped as shown and may be constructed economically of galvanized iron or the like, has vertically disposed within it, and respectively adjacent its end walls, two guide rods 11, 12. These rods, which may be of brass and soldered in place at their ends, are respectively surrounded by coil springs 13, 14, suitably made of brass, or other like resilient metal, and of such character that they may be compressed into a relatively small space near the bottom of the tank and also if desired, such that they will be under at least some compression even in the position shown in Fig. 2. A movable trough-shaped support 15 having holes 16, 16 through which the rods 11, 12 may pass, is carried by the upper extremities of springs 13, 14, and may have in it suitable apertures such as the holes 17 conveniently disposed along the central portion thereof, to permit free passage of water or other liquid therethrough when the support is pushed downwardly into the tank (see Fig. 3). This support 15, constantly urged upward by the springs 13, 14, is prevented from rising above a predetermined position by the guard plates 18, to which when disposed as shown, for example, the upper ends of the guide rods 11, 12 may be fixed by soldering, or the like.

To hold the stiffening pieces for submergence in the tank and subsequent softening, racks may be provided such as the plate 19, of galvanized iron or other suitably rigid material. In vertical slots 20 in such a plate there may be soldered or brazed one or more coil springs 21, of the close type, such as hereinabove described with respect to the apparatus of my aforesaid copending application, so that adjacent turns will form spring clips for holding the stiffening pieces 22, as shown in Fig. 4. It may also be desirable to have the convolutions of these springs slope downwardly, to hold the pieces in correspondingly inclined position.

The tank 10 is open at the top as shown and the plate or rack 19 is of such proportions that it may be inserted in the tank with its bottom edge resting in the central depression or channel of support 15 (see Fig. 2). When so positioned the rack may then slope back against one of the upper edges of the side walls of tank 10, and the slanting position of springs 21, while somewhat modified by the slope of the rack, will still be such that water or other liquid may effectively drain off the stiffening pieces 22 carried by the springs. The tank 10 may have a suitable galvanized iron bail 23 for carrying it from place to place and the rack 19 may be provided with a hook-like handle 24, which latter may have a sharp outer edge so as to obtain a frictional grip on

the work bench or other table on which the rack may be placed when removed from the tank, and thus to facilitate removal or insertion of the stiffening pieces.

In using the apparatus the tank 10 is filled with water, indicated at 25, up to a suitable point, conveniently to about the level of support 15 when the latter is in its uppermost position. On the plate or rack 19 the several stiffening pieces which are to be softened may be mounted and the rack placed in the position shown in Fig. 2. This may conveniently be done at any time, whether or not it is desired to soften the pieces immediately. When the workman is ready to perform the mulling operation he then grasps the plate 19, as by its handle 24, and pushes it downwardly on support 15 and against the force of springs 13, 14, into the tank, so that the stiffening pieces are there submerged in the water as desired. This operation taking only a few moments, the workman then withdraws the rack 19 and allows it to rest in the position of Fig. 2, while water received by the stiffening pieces soaks in to soften them, and any excess drains off. The mulling operation may then continue with the rack in this position, or removed to another appropriate receptacle or place, as long as convenient,—preferably until the "toes" have become suitably damp and soft throughout, and their surface wetness has substantially disappeared so that in using them, the workman's fingers will not become moist and consequently soil or otherwise damage the shoes he is working on.

It will now be understood that in using the apparatus of the present invention, a workman cannot accidentally leave the stiffening pieces in the water any longer than the moment or two necessary to wet them. If he is suddenly called away, for instance, while holding a rack down in the tank, he will necessarily permit it to be forced upward on support 15 by the springs and to rest in a position such as that shown, before he leaves. In other words, a rack cannot remain in the tank by reason of neglect or forgetfulness, since it can only stay there when held down by the operator, and consequent over-softening or other injury to the stiffeners is avoided. Furthermore, the apparatus serves as a simple and efficient structure for effecting the mulling operation, and may provide convenient and satisfactory means for holding the stiffeners, during the entire time of that operation and until it is necessary to remove them for actual use in making shoes. On the other hand, by reason of its simplicity of construction and the accessibility of its means for receiving the racks, the apparatus may be rapidly and repeatedly used for submerging any number of racks in succession, each such operation being accomplished with practically a single motion, and

there being no operative parts to be adjusted by the workman.

It is to be understood that the invention is not limited to the apparatus herein specifically illustrated and described but can be embodied in other forms without departure from its spirit as defined by the following claims.

I claim:

1. Apparatus for softening box-toe stiffening pieces capable of being softened by temporary submergence in a body of water and by subsequent absorption of the water retained therefrom, including a relatively narrow tank with a pair of relatively closely spaced walls, vertically disposed members in said tank, a trough-shaped member slidable upon said vertical members and extending into relatively close proximity to the aforesaid walls, so as to be vertically guided thereby, a rack for stiffening pieces removably associative with said trough shaped member, and adapted for vertical introduction into the tank, and resilient means adapted to be compressed upon depression of the trough-shaped member by forced introduction of the rack into the tank, and also adapted to extend to elevate the trough-shaped member and the like upon removal of pressure from the rack.

2. Apparatus for softening box-toe stiffening pieces capable of being softened by temporary submergence in a body of water and by subsequent absorption of the water retained therefrom, comprising a relatively narrow tank with relatively closely spaced front and rear walls, a movable rack assemblage for holding stiffening pieces, a member vertically slidable in the tank with portions extending into proximity to the walls thereof for guiding action and a portion for centralizing the movable rack assemblage and guiding the latter into the tank, and resilient means cooperating with the vertically slidable member arranged to be compressed upon the introduction of the rack assemblage into the tank and adapted for automatic distention to expel the rack assemblage from the tank upon release of pressure upon the rack assemblage.

3. Apparatus for softening box-toe stiffening pieces capable of being softened by temporary submergence in a body of water and by subsequent absorption of the water retained therefrom, comprising a relatively flat rack for holding a plurality of stiffening pieces, a tank constructed to permit insertion of said rack in vertical position with the stiffening pieces submerged in water therein, a rack-supporting member vertically slidable in the tank and having a configuration adapted to readily guide the racks into position for submergence guide means in the tank for maintaining the said member in rack-supporting and positioning relation, and resilient means in the tank cooperating with said member and said guide means, arranged to

be compressed on insertion of the rack into the tank and adapted for automatic distention to raise the rack clear of water in the tank when pressure upon the rack is released.

4. Apparatus for softening box-toe stiffening pieces capable of being softened by temporary submergence in a body of water and by subsequent absorption of the water retained therefrom, including a relatively narrow upright tank, and a trough-shaped member vertically slidable in the tank and capable of readily receiving and supporting therein one edge of a flat rack carrying stiffening pieces, a separable rack vertically insertible in the tank, said tank being constructed for guiding and maintaining the slidable trough shaped member in rack receiving and supporting position, and resilient means in the tank adapted to be compressed upon depression of the trough-shaped member by insertion of said rack into the tank and also adapted to expand to elevate the trough shaped member and the rack upon removal of pressure from the rack.

In testimony whereof I hereto affix my signature.

HARRY FRANK ROSE.
